UNITED STATES PATENT OFFICE

2,516,327

METHOD OF LAUNDERING

George Kuhn, Silver Spring, Md., assignor to
General Motors Corporation, Dayton, Ohio, a
corporation of Delaware

Original application March 7, 1942, Serial No.
433,818, now Patent No. 2,397,873, dated April
2, 1946. Divided and this application June 7,
1943, Serial No. 489,971

1 Claim. (Cl. 8—159)

1

This invention relates to the washing and cleaning of fabrics and articles and more particularly pertains to a method of washing fabrics in power driven washing and cleaning machines.

An object of this invention is to provide a method of laundering articles in which the articles are submerged in a body of washing fluid and in which body of fluid alternate series of upper and lower radially outward impulses are created in a central vertical zone occupying a minor portion of the lateral extent of said body of washing fluid.

This application is a division of my copending application Serial No. 433,818, filed March 7, 1942, now Patent No. 2,397,873, issued April 2, 1946, which, in turn, is a continuation in part of application Serial No. 164,820, filed September 20, 1937, now Patent No. 2,275,444, issued March 10, 1942.

The features and advantages of the invention will be apparent from the following description when considered in connection with the accompanying drawings, forming a part thereof, and in which:

Fig. 1 is a vertical sectional view of a washing machine for performing the method of this invention;

Fig. 2 is a vertical sectional view of part of the machine taken on line 2—2 of Fig. 1;

Fig. 3 is a vertical sectional view, similar to Fig. 1, showing another form of washing machine; and

Fig. 4 is a sectional view taken on line 4—4 of Fig. 3.

Like characters of reference refer to the same or similar parts throughout the several views.

Referring to Figs. 1 and 2 of the drawings, reference character 10 designates the tub of the washing machine which is preferably cylindrical in form with a closed bottom 11 and an opening 12 at the top which is closed by a hinged cover 13. The tub is supported on a suitable pedestal indicated 14. The bottom of the tub has a raised central portion 15 and a drain 16 connects with the lowermost part of the bottom 11.

The fluid circulating or propelling means is axially disposed in the tub 10 and, in general, comprises a pulsator consisting of a hollow tubular member such as a cylinder 17 and an element such as a piston 18, and a fluid propelling and directing piston skirt 19. The cylinder 17 is of metal and has a closed upper end and an open lower end around the outer periphery of which is a ring 20 of rubber or other suitable material. The cylinder is secured on the upper

2

end of a reciprocable shaft 21 which passes through the upper end of the cylinder and the lower end of the cylinder is submerged so long as the water or other fluid 22 is maintained at substantially the level shown in Figs. 1 and 2. The inner and outer walls of the cylinder are disposed parallel to the direction of motion of the cylinder and during normal operation the cylinder is neither completely submerged nor entirely out of the fluid so that splashing is prevented. The pulsator piston 18 is a cylindrical metallic member shaped similarly to the cylinder 17 but is of sufficiently smaller diameter to provide an annular opening 23 of substantial flow area between the cylinder and piston through which the fluid readily may flow. The piston is axially disposed with respect to the cylinder and is mounted on a fitting 23, preferably a die casting, which is fixed to the upper end of a piston sleeve 24 through which shaft 21 passes and upon which the sleeve bears at its upper end. Shaft 21 passes in a smooth running fit through a collar 25 carried by the upper closed end of the piston 18. The fluid propelling and directing skirt 19 has an outer surface which curves gradually outwardly and downwardly and has a metallic upper part and a flexible fin 26 which is preferably rubber but may be of other suitable flexible material, secured to the upper part. The upper end of the skirt 19 is secured to the fitting 23 and the skirt is axially disposed with respect to the piston 18 and cylinder 17. The piston skirt 19 may be made integral with or separate from the piston 18 and may have other shapes than that disclosed. For example, the outer surface of the skirt may be shaped so that it is horizontal, or approximately so, with a fin on its periphery which extends downwardly and outwardly like the fin 26. This horizontal skirt is effective for the purpose because the opposing streams of fluid from the upwardly moving skirt and from the cylinder will meet and be thrown radially outwardly. Shaft 21 and sleeve 24 extend through an opening in the bottom 11 of the tub to the operating mechanism disposed beneath the tub. To prevent leakage of fluid through this opening and to eliminate the necessity of a stuffing box, upper and lower bellows 27 and 28 of rubber or other fluid-proof flexible material are used. The upper end of the upper bellows 27 is secured by means of a metallic ring 29 or the like in fluid pressure tight relationship to shaft 21 at a point which will not interfere with the movement of the piston 18, and the lower end is similarly fixed to the

upper portion of fitting 23. The upper portion of bellows 28 is also similarly fixed to the lower end of fitting 23 and the lower end is fixed to a neck 30 on the operating mechanism housing 31 through which the sleeve 24 and shaft 21 pass. A nut 32 threaded on neck 30 compresses packing material against the bottom 11 of the tub which is pressed against the upper part of the housing 31 thereby preventing leakage of fluid at this point. A plurality of air vents 33 pass through fitting 23 next to sleeve 24 to connect the chambers formed by the upper and lower bellows 27 and 28 to relieve air pressure and vacuum produced during operation. The fitting 23 is also provided with a plurality of water vents 34 next to the walls of the pulsator piston to relieve water pressure in the upper portion of the pulsator piston during operation. In place of the lower bellows 28, a diaphragm, of rubber or other suitable material, of the type disclosed in my copending application Serial No. 106,080, filed October 17, 1936, may be used.

The fluid circulating or propelling means is driven by a reversible electric motor 36 through mechanism which is mechanically balanced and the parts of which move with complete symmetry of motion during all phases of the operative cycle. This mechanism has been illustrated and operates in the same manner as illustrated and described in my said Patent 2,275,444. Corresponding parts have been numbered as in said patent and their operation is described therein, and hence is not here repeated.

The pulsator piston and cylinder and the skirt 19 are rapidly reciprocated with relatively short strokes. The movement of the members 17, 18 and 19 should be materially faster than it is possible for the articles being treated to follow such movement. Good results are obtained with a speed of the eccentric shaft of 500 R. P. M. with strokes of the reciprocating elements of 1½ in. to 1¾ in., but satisfactory results will be obtained at speeds between 400 and 650 R. P. M. with the same stroke. The stroke in the form of the invention shown in Figs. 1 and 2 may be varied between 1 in. and 1¾ in. with satisfactory results.

During operation, the clothes are placed in the outer unrestricted portion of the body of liquid in the tub and on the upstroke of the cylinder 17 and the downstroke of the piston 18, fluid is sucked into the cylinder from all directions which draws the articles in the upper portion of the fluid radially inwardly toward the cylinder. Any jet action produced at this point is into the restricted portion of the body of liquid in cylinder 17 and produces very little circulating effect on the unrestricted portion of the body surrounding cylinder 17. At the same time, the skirt 19 has moved downwardly and has forced fluid from below the skirt in a jet action into the unrestricted portion of the body of liquid surrounding the skirt, radially outwardly along the bottom of the tub. On the downstroke of the cylinder and the upstroke of the piston, fluid is expelled from the cylinder in the form of an annular jet having a downward direction parallel to the wall of the cylinder through the annular opening 97 and against the upwardly moving, outwardly and downwardly curving surface of the skirt 19 which deflects the fluid jet downwardly and radially outwardly in the unrestricted portion of the body of liquid in the lower portion of the tub, with gradually increasing velocity as it moves over the skirt. On each

upstroke of the skirt 19 fluid is forced with a jet action outwardly and downwardly thereof from the space within the cylinder 17 into the unrestricted portion of the body of liquid due to the action of the upper surface of the skirt, and fluid is also drawn under the skirt with a jet action directed into the restricted portion of the body of liquid and is expelled on the downstroke with a jet action into the unrestricted portion 10 of the body of liquid as previously described, along the bottom of the tub. Due to the flexibility and downward inclination of the fin 26 on the skirt 19, it pumps fluid toward the bottom of the tub in the upper portion of its downward stroke, while in the lower portion of its downward stroke it flattens out due to the jet-like radial flow of water from under the skirt 19 thus allowing free escape of the fluid from under the skirt. The use of the fin also makes it possible to bring the skirt almost into contact with the bottom of the tub at the end of its downstroke without danger of injury to one who might put his hand under it, whereby it functions as a safety feature. With rapid reciprocation of these elements 17, 18 and 19, the fluid is subjected to a series of unidirectional, intermittent jerks or pushes in the form of outward jets into the unrestricted portion of the body of liquid which result in the fluid and the articles therein being continually moved in unidirectional circulatory paths about these elements in directions radially outwardly along the bottom of the tub, upwardly along the wall thereof, radially inwardly at the upper portion of the body of fluid and downwardly along the cylinder 17 and piston 18 as indicated by the direction-of-flow arrows in Fig. 1. These short, fast fluid jerks, pushes, jets, or squirts originate at the open edge of the pulsator cylinder and at the edge of the skirt and set up a series of rapid pulsations in the unrestricted portion of the body of the fluid which spread throughout the unrestricted portion of the body of the fluid and result in the pulsing or forcing of the fluid through the fabric of articles being treated. On the suction strokes the jets are inwardly directed into the restricted portion of the body of fluid, and fluid is withdrawn from the unrestricted portion, but not in jet form. Hence the circulation in the unrestricted portion is dominated by the outward jets and is in the direction illustrated by the arrows in Fig. 1. The outward jets also cause rapid shaking and flexing of the articles being treated with consequent scrubbing due to the rubbing of the articles on one another and rubbing of parts of each article on other parts thereof in the active zones adjacent the open lower end of the pulsator cylinder 17 and at the lower edge of the skirt 19. As the articles move into the aforesaid active zones, the end of an article first coming under the influence of the zone adjacent the pulsator cylinder is vigorously shaken, scrubbed and jerked and gradually fed downwardly. These jerks spread through the articles so that its other portions and other end are liberated from the other articles which have not yet entered said zone, thus untangling the article. At the beginning of the fluid treating operation, the action of the pulsator on the fluid heretofore described breaks up bubbles of air in articles such as clothes and the like, which if left unbroken would cause the articles to float on the top of the fluid, and pushes the articles under the surface of the fluid. The scrubbing action produced by the machine,

results primarily from the vigorous flexing and shaking of the articles as previously described during the circulatory movement.

As an illustrative example, but without limiting effect, a washing machine embodying the form of the invention heretofore described and having the dimensions set forth, when operated at speeds between 450 and 500 R. P. M. with a full load of eight pounds of clothes, completed the wash in ten minutes without previous soaking of the clothes. Pulsator cylinder—4 in. in diameter and $7\frac{1}{8}$ in. in axial length. Pulsator piston— $2\frac{3}{4}$ in. in diameter and 6 in. in axial length to the piston skirt. Piston skirt without fin— $6\frac{1}{2}$ in. bottom diameter and $2\frac{1}{4}$ in. in axial length. Fin on skirt— $8\frac{3}{4}$ in. in its outermost diameter. Mechanism stroke— $1\frac{1}{4}$ in. With previous soaking of the clothes, the washing time would be less than ten minutes. Actual tests with this machine have resulted in washings at least $33\frac{1}{3}\%$ faster than the washing time required by conventional washing machines now on the market in a ten minute washing test, with 20% less wear on the washed clothes, measured by the amount of lint collected after two hours of continuous washing.

In the form of the invention disclosed in Figs. 3 and 4, the arrangement of the fluid circulating or propelling means is the same as the other form shown in Fig. 1, excepting that the pulsator cylinder 80 is stationary. The operating mechanism is illustrated, numbered, and operates as in said Patent 2,275,444. In operation, on the upstroke, the skirt 19 moves a volume of water downwardly from the cylinder 80 parallel to the wall of the cylinder and against the curved upper surface of the skirt 19. The sizes of the pulsator cylinder and piston and the skirt 19 are so proportioned that the two actions just described neutralize each other thereby producing hydraulic balance. On the downstroke, fluid is sucked into the cylinder 80 from all directions so that no hydraulic unbalance results. Also on the downstroke, the skirt 19 ejects fluid radially therefrom along the bottom of the tub which also results in no hydraulic unbalance. In this form of the invention, as in the other form, both mechanical and hydraulic balance are maintained at all times. To provide the same fluid displacement per stroke and the same downward speed of the fluid ejected from the cylinder as in the other embodiment shown in Fig. 1, the cross-sectional area of piston 18 should be twice that of the piston in Fig. 1 and the area of the cylinder 80 should be sufficiently great so that the flow area of the annular clearance 97 between the piston and the cylinder will be the same as in Fig. 1. This follows from the fact that in this embodiment the stroke of the fluid circulating and propelling means is one-half of that in Fig. 1, due to the fact that the cylinder 80 is stationary. For example, if the piston of Fig. 1 is $2\frac{3}{4}$ in. in diameter and the cylinder 4 in. in diameter, the piston in Fig. 3 should be approximately $3\frac{3}{8}$ in. in diameter and the cylinder $4\frac{1}{8}$ in. in diameter. Otherwise, the proportions of the several parts are the same as in the other form, and the results obtained are the same as described in connection with the other form, including the unidirectional circulatory movement of the fluid and the articles being treated and the washing action produced which comprises

pulsating of the fluid through the fabric of the articles, the flexing and shaking of the articles which produces rubbing contact of the articles as previously described with consequent scrubbing of the articles on themselves, together with the separating and untangling of the articles resulting from the pulling forces produced by the series of short fast fluid jerks produced by the action of the pulsator cylinder and the piston.

- 5 During the first few strokes of the fluid circulating or propelling means in both forms disclosed, the air is knocked out of the cylinder, after which the action is entirely hydraulic.

It will be apparent to those skilled in the art that changes may be made in the form, location, relative arrangement and the materials of the several parts of the machine disclosed without departing from the principles of the invention. Accordingly, it will be understood that the invention is not to be limited excepting by the scope of the appended claim.

The method of laundering articles to be washed which comprises submerging said articles in a body of washing liquid, maintaining an upper and lower barrier in the lower central restricted portion of said body, permitting unrestrained lateral and radial flow of liquid and articles to be washed from said portion of said body and producing rapid alternating upward and downward impulses in said liquid between said barriers to produce two vertically spaced series of outward jet-like impulses of liquid into the outer unrestricted portion of said body and inward impulses into said central restricted portion together with portions of articles to be washed alternately at upper and lower zones respectively from between said upper and lower barriers whereby liquid in said unrestricted portion is subjected to a series of unidirectional, intermittent jets which result in the fluid and the articles therein in said unrestricted portion being continually moved in unidirectional circulatory paths about the central restricted portion of said body in directions radially outwardly along the bottom of said body, upwardly along the outer boundary of said body, radially inwardly at the upper portion of said body and downwardly along the central restricted portion of said body together with a continuous rubbing of articles to be washed adjacent said jets.

GEORGE KUHN.
